Inventor:
Arthur G. Zimmerman,
by *Myron S. Zim*,
His Attorney.

UNITED STATES PATENT OFFICE

ARTHUR G. ZIMMERMAN, OF SCHENECTADY, NEW YORK, ASSIGNEE TO GENERAL ELECTRIC COMPANY, A CORPORATION OF NEW YORK

APPARATUS FOR THE INTERCONVERSION OF SOUND AND ELECTRICAL IMPULSES

Application filed October 8, 1927. Serial No. 224,873.

My invention relates to apparatus for the interconversion of sound and electrical impulses, and has for its principal object the provision of an improved means for adjusting the mechanical relation between the various parts of such an apparatus.

Many different types of apparatus for the interconversion of sound and electrical impulses have been provided in the past. Some of these apparatus comprise a coil which is arranged to be moved in a magnetic field either for producing sound impulses which are dependent on electrical impulses or for producing electrical impulses which are dependent on sound or on the contour of a sound record.

When a coil is arranged to be moved in a magnetic field, difficulty is frequently encountered in producing and maintaining the proper spacing between the movable coil and the pole members through which the magnetic field is produced. In accordance with my invention, this difficulty is avoided by the provision of an improved means for adjusting and maintaining the position of the coil in the magnetic field.

My invention will be better understood from the following description when considered in connection with the accompanying drawings and its scope will be pointed out in the appended claims.

Referring to the drawings, Figs. 1 to 3 show different views of a sound producing apparatus wherein my invention has been embodied.

This apparatus comprises a conical diaphragm 1 which is provided with a collar 2 for supporting a movable coil 3 and is mounted within a casing 4. At its outer periphery 40 this diaphragm is attached to a flexible member 5 of velvet, or the like, which has its outer edge clamped between the casing 4 and a member 6 by means of screws 7. With this arrangement, the diaphragm 1 is loosely held within the casing and is permitted to move freely in response to electrical impulses applied to the coil 3 or in response to sound impulses applied to the diaphragm.

The coil 3 is supported in an annular air gap between the poles 8 and 9 of a magnet

which is supported on a base 10 and may be provided with a field coil 11. The casing 4 is clamped to the pole piece 8 by means of screws 12, and the position of the coil in the air gap is determined by tensile forces applied to a 55 plurality of cords 13 which are knotted together at the center of the collar 2 and are given one turn around a cord 14, which is glued or otherwise attached to the diaphragm 1.

Adjustment of the coil 3 in the annular air gap is effected by means of screws 15, which are supported upon the casing 4 through brackets 16 and are arranged to wind up or unwind the ends of the cords 13. 60 The brackets 16 are preferably but not necessarily made of brass or other nonmagnetic material and are split as indicated, or are otherwise formed to produce friction whereby the screws 15 are positively locked in any 70 position to which they are turned. It will be apparent that this improved means for adjusting the position of the movable coil has the advantage that the adjustment is readily made from the front of the diaphragm where 75 the spacing between the pole piece 9 and the collar 2 is readily observed. It will of course be understood that the cords 13 permit the coil 3 to move freely in a direction along the axis of the pole piece and coil.

The embodiment of the invention illustrated and described herein has been selected for the purpose of clearly setting forth the principles involved. It will be apparent, however, that the invention is susceptible of 80 being modified to meet the different conditions encountered in its use and I therefore aim to cover by the appended claims all modifications within the true spirit and scope of 85 my invention.

What I claim as new and desire to secure by Letters Patent of the United States is:—

1. The combination of a casing, a diaphragm attached to said casing through a flexible connection, a coil mounted on said diaphragm, and means mounted on said casing for adjusting the position of said coil from the front of said diaphragm.

2. The combination of a casing, a diaphragm attached to said casing through a 100

flexible connection, a coil mounted on said diaphragm, a plurality of cords connected to said diaphragm, and means for controlling the tension of said cords from the front of said diaphragm.

5 3. The combination of a casing, a diaphragm attached to said casing through a flexible connection, a coil mounted on said diaphragm, a plurality of cords connected to said diaphragm for adjusting the position of said coil, means for controlling the tension of said cords from the front of said diaphragm, and means for producing a magnetic field intercepting said coil.

10 4. The combination of a casing, a diaphragm attached to said casing through a flexible connection, a coil mounted on said diaphragm, a bracket mounted on said casing, a member threaded into said bracket, and flexible means connected to said diaphragm and arranged to be subjected to a tension controlled by said threaded member for adjusting the position of said coil.

15 5. An acoustical device comprising magnetic means provided with an air gap, a casing, a diaphragm attached to said casing through a flexible connection, a coil supported within said air gap by said diaphragm, and means for adjusting the position of said coil in said air gap from the front of said diaphragm.

20 6. The combination of a casing, a diaphragm attached to said casing through a flexible connection, a coil mounted on said diaphragm, a plurality of cords connected to said diaphragm, and means comprising a plurality of members threaded into said casing and arranged to be turned from the front of said diaphragm, said cords being wound 25 upon said threaded members for adjusting the position of said coil in said air gap.

30 In witness whereof, I have hereunto set my hand this 7th day of October, 1927.

ARTHUR G. ZIMMERMAN.
